US00D894389S

(12) **United States Design Patent** (10) **Patent No.:** **US D894,389 S**
Shelton, IV et al. (45) **Date of Patent:** **** Aug. 25, 2020**

(54) **SURGICAL FASTENER**

- (71) Applicant: **Ethicon LLC**, Guaynabo, PR (US)
(72) Inventors: **Frederick E. Shelton, IV**, Hillsboro, OH (US); **Jason L. Harris**, Lebanon, OH (US); **Gregory J. Bakos**, Mason, OH (US); **Chester O. Baxter, III**, Loveland, OH (US)
(73) Assignee: **Ethicon LLC**, Guaynabo, PR (US)
(**) Term: **15 Years**
(21) Appl. No.: **29/660,275**
(22) Filed: **Aug. 20, 2018**

Primary Examiner — Wan Laymon

(57) **CLAIM**

The ornamental design for a surgical fastener, as shown and described.

DESCRIPTION

FIG. 1 is a perspective view of a surgical fastener. FIG. 2 is a front elevation view of the surgical fastener of FIG. 1. FIG. 3 is a rear elevation view of the surgical fastener of FIG. 1. FIG. 4 is a top plan view of the surgical fastener of FIG. 1. FIG. 5 is a bottom plan view of the surgical fastener of FIG. 1. FIG. 6 is a left elevation view of the surgical fastener of FIG. 1. FIG. 7 is a right elevation view of the surgical fastener of FIG. 1. FIG. 8 is a perspective view of a surgical fastener. FIG. 9 is a front elevation view of the surgical fastener of FIG. 8. FIG. 10 is a rear elevation view of the surgical fastener of FIG. 8. FIG. 11 is a top plan view of the surgical fastener of FIG. 8. FIG. 12 is a bottom plan view of the surgical fastener of FIG. 8. FIG. 13 is a left elevation view of the surgical fastener of FIG. 8; and, FIG. 14 is a right elevation view of the surgical fastener of FIG. 8.
